UNITED STATES PATENT OFFICE

SCHACHNO PEISACH SCHOTZ, OF LONDON, ENGLAND

BLEACHING AGENT AND METHOD OF PRODUCING SAME

No Drawing. Application filed December 15, 1930, Serial No. 502,519, and in Great Britain November 28, 1929.

This invention relates to bleaching agents for flour, other milling products and starches and to a method of producing same.

In the following specification and claims 5 the term "acid halogenides" is intended to mean compounds having the formula of organic acids with the exception that the OH group of the COOH group is replaced by a halogen; and includes mixtures giving rise 10 to "acid halogenides".

The object of the new invention is to provide a new method of preparing bleaching materials of this kind in which bleaching compounds mentioned hereafter are produced direct by mixing a number of ingredients together.

According to the present invention the bleaching is accomplished by intimately mixing 20 aldehydes, substituted aldehydes or materials containing or setting free aldehydes with acid halogenides in absence of water and introducing said mixture, during or after the resulting reaction, into the flour or other material to be bleached.

25 It is convenient to employ the substances which are essential for the production of the bleaching compounds in proportions corresponding to their molecular weights but this is not essential.

30 In most cases it will be preferable, or even necessary, to introduce the reaction mixture thus obtained into a finely powdered mixture of a suitable base adapted to facilitate the reaction. The bases would be chosen according 35 to the materials to be treated by the new compound. In lieu of the bases in certain cases I may use salts of weak acids decomposed under conditions of the process, metals such as powdered zinc, magnesium, aluminum or calcium.

40 In order partly to accelerate the reaction, partly to assist in removing any impurities there may be in the aldehyde substances or in the acid halogenide substances and partly 45 with a view to promoting the bleaching action of the compound which is obtained it is advantageous to add halogenating agents, such as phosphorus pentachloride, phosphorus pentabromide, phosphorus trichloride, phosphorus oxychloride, anhydrous alu-

minium chloride, thionyl chloride, bleaching powder, chloramine-T, dichloramine-T, potassium chlorate, potassium perchlorate, and the like.

Persalts may also be introduced.

To facilitate the reaction, bodies such as 55 kieselguhr, silica gel, china clay, alumina, activated earths and other substances acting as catalysts or diluents may be added before, during or after the reaction. Liquid diluents and solvents may be added if desired 60 provided they do not decompose the reacting bodies or the product under the conditions of manufacture.

The substances are mixed together 65 preferably in such a manner that atmospheric air and moisture shall not interfere with the reacting bodies and the mixture is allowed to stand for some time (depending on the materials used, the temperature and the method of grinding) preferably with occasional mixing, after which the bleaching agent is 70 ready for use.

It is not necessary to wait until the reaction is complete before introducing the mixture into the material to be bleached. If this course is adopted the active principle continues to be formed while the bleaching is 75 proceeding.

Materials which absorb moisture such as 80 phosphorus pentoxide and the like are a valuable addition to absorb any trace of moisture.

Elevated temperatures assist the reaction 85 provided the temperatures are not high enough to bring about the decomposition of any of the bleaching agents obtained. If desired the bleaching compounds could be isolated or reduced in quantity by extraction with suitable solvents, or other known chemical means.

The following three lists give an indication 90 of the bodies which can be employed to carry out the improved method.

Aliphatic, alicyclic and aromatic aldehydes 95 may be used, such as acetaldehyde, propaldehyde, chloracetaldehyde, benzaldehyde, o-, m- and p-chlorobenzaldehyde, ethyl benzaldehyde, o-tolyl aldehyde, m-tolyl aldehyde, p-tolyl aldehyde, their homologues, substi- 100

1072

1,836,134

tution products and combinations thereof and substances yielding same.

Aliphatic, alicyclic and aromatic acid halogenides may be employed, such as acetyl chloride, acetyl bromide, chloracetyl chloride, benzoyl chloride, benzoyl bromide, benzoyl iodide, also o-tolyl chloride, m-tolyl chloride, p-tolyl chloride, phenylacetyl chloride.

As basic bodies for the purposes of this invention it is possible to employ oxides, peroxides and hydroxides of the alkalies and alkaline earths, of zinc or of other metals easily attacked by halogen acids or their carbonates, bicarbonates, sesquicarbonates or salts of other weak acids; for example, the carbonates and bicarbonates of lithium, soda, potash, ammonia, the carbonates, the oxides, peroxides and hydroxides of lime, magnesia, zinc, cerium, thorium, their formates, acetates, benzoates, and salts of other weak acids such as tungstic, vanadic, molybdic and titanic acids.

The following examples will serve to illustrate various ways of carrying out the present invention but it is to be understood that the scope of the invention is not to be limited by these examples.

Example 1

15 parts of dehydrated soda are mixed with 30 18 parts of dehydrated magnesium carbonate and into the mixture thus obtained are introduced 5 parts of purified benzaldehyde and 6 parts of benzoyl chloride. The ingredients are ground together at ordinary temperature with exclusion of moisture in a closed container having a suitable outlet for any gases formed during the reaction and allowed to stand with occasional grinding for several 35 days until the smell of benzoyl chloride has nearly disappeared. The product is a powdery mass which has good bleaching properties for flour.

Example 2

45 To the constituents mentioned in Example 1 are added 1.1 parts of sodium ortho vanadate and the ingredients are mixed as in Example 1. It would seem that the product obtained with the addition of the vanadate 50 compound has rather better bleaching properties for flour than the product obtained without the addition of this vanadate compound.

Example 3

55 Instead of allowing the mixture produced in Example 2 to react at ordinary temperature, the mass obtained on grinding together the ingredients was heated for one and a half hours at about 50° C. in a container of the nature described in Example 1. A very good bleaching compound for flour was obtained.

Example 4

To the benzaldehyde and benzoyl chloride mentioned in Example 1 are added 0.5 parts

of thionyl chloride and the process carried out as in Example 1. A good bleacher is obtained.

Example 5

6 parts of ortho-chlorobenzaldehyde are mixed with 6 parts of benzoyl chloride and introduced into a mixture of 15 parts anhydrous soda, 18 parts magnesium carbonate, and 1.12 parts sodium ortho vandadate, and 75 the process carried out as in Example 1. A powerful bleaching compound for flour is obtained.

The proportions of soda and magnesium carbonate in the above examples are arbitrary 80 and can be varied at will within very wide limits.

Example 6

5 parts of benzaldehyde are mixed with 6 parts of benzoyl chloride and the solution introduced into a dry finely powdered mixture of 6 parts potassium bicarbonate, 10 parts magnesium carbonate, 8 parts sodium carbonate and 1 part sodium tungstate and 90 the ingredients ground together in a container referred to in Example 1.

After 48 hours standing the mixture is ground again and heated to about 50° C. until most of the smell of benzoyl chloride has 95 disappeared.

An excellent bleaching material for flour is obtained.

Example 7

100 A freshly made solution of 5 grams acetyl chloride and 10 grams benzaldehyde is introduced into a dry mixture of 7.5 parts soda, 8.5 parts potassium bicarbonate, 6.5 parts magnesium carbonate, 1 part cerium carbonate and 105 thoroughly incorporated by grinding. After standing for 2 days at room temperature as in Example 1, it is heated for 24 hours between 30-50° C. An efficient though somewhat slow bleacher is obtained.

Example 8

5 grams benzaldehyde were mixed with 6 grams benzoyl chloride and 0.6 grams of anhydrous aluminium chloride and heated 115 for 1½ hours at about 100° C.

After standing overnight 5 grams of the mass obtained were intimately mixed with 15 grams kieselguhr free from iron and organic matter.

When mixed with flour this material exerted a distinct bleaching effect.

The choice and total quantity of the ingredients in each case would be governed by costs, reactivity, poisonous nature, degree of 125 unpleasantness, ease of handling, hygroscopicity, purpose for which the product is required and such like practical considerations. The product obtained according to any of the above examples should be applied to the 130

substance to be bleached, for example flour, in a finely divided condition.

I am aware that it has previously been proposed in connection with the decolourizing of woven cotton fabrics to employ monobenzylparasulphochloride with the addition of sodium hydrosulphite-formaldehyde along with the usual liquors or lyes of milk of lime or the like, together with other suitable compounds such as anthraquinones.

Having now particularly described and ascertained the nature of my said invention and in what manner the same is to be performed I declare that what I claim is:

15. 1. Method of producing bleaching agents for flour and other milling products, consisting in forming a dry mixture of aldehydes and acid halogenides, intimately mixing these constituents with basic bodies and adding to the mixture halogenating agents and persalts.
20. 2. Method of producing bleaching agents for flour and other milling products, consisting in forming a dry mixture of substituted aldehydes and acid halogenides, intimately mixing these constituents with basic bodies and adding to the mixture halogenating agents.
25. 3. Method of producing bleaching agents for flour and other milling products, consisting in forming a dry mixture of substituted aldehydes and acid halogenides, intimately mixing these constituents with basic bodies and adding to the mixture persalts.
30. 4. Method of producing bleaching agents for flour and other milling products, consisting in forming a dry mixture of aldehydes and acid halogenides, intimately mixing these constituents with basic bodies, adding halogenating agents and adding bodies such as kieselguhr, silica gel, china clay, alumina and activated earths.
35. 5. Method of producing bleaching agents for flour and other milling products, consisting in forming a dry mixture of benzaldehyde and benzoyl chloride, intimately mixing these constituents with magnesium carbonate and adding thereto sodium orthovanadate.
40. 6. Method of producing bleaching agents for flour and other milling products, consisting in forming a dry mixture of benzaldehyde and benzoyl chloride, and intimately mixing these constituents with a carbonate
45. 55. of a metal selected from the group consisting of the alkali and alkali earth metals.
50. 7. A method of producing bleaching agents for flour and other milling products consisting of forming a dry mixture of aldehyde and acid halogenides, and intimately mixing these constituents with a carbonate of a metal selected from the group consisting of the alkali and alkali earth metals.

SCHACHNO PEISACH SCHOTZ.
